UNITED STATES PATENT OFFICE.

JOHN CLAYTON BACKUS, OF SMETHPORT, PENNSYLVANIA.

SASH-LOCK.

1,172,663.

Specification of Letters Patent.

Patented Feb. 22, 1916.

Application filed August 28, 1915. Serial No. 47,799.

To all whom it may concern:

Be it known that I, JOHN CLAYTON BACKUS, a citizen of the United States, residing at Smethport, in the county of Mc- 5 Kean and State of Pennsylvania, have invented certain new and useful Improvements in Sash-Locks, of which the following is a specification.

This invention relates to sash locks and 10 the object of the invention is to provide a simple, inexpensive and efficient device which may be readily applied to any window and effectually lock the same against opening from the outside of the building, 15 while at the same time permitting it to be adjusted to an open position by a person within the room.

One object of the invention is to provide 20 a device for the stated purpose which, when in use, will be substantially concealed between the sash and the window frame and which will not interfere with the proper movement of the sash.

The invention is illustrated in the accompanying drawings and consists in certain 25 novel features which will first be fully described and then more particularly pointed out in the claims following the description.

In the accompanying drawings: Figure 1 30 is a perspective view of a portion of a window, showing my improved lock applied thereto; Fig. 2 is an enlarged front elevation with parts broken away and in section; Fig. 3 is a horizontal section on the line 35 3—3 of Fig. 2; Fig. 4 is a detail perspective view of the parts of the device disassembled but in their approximately relative positions; Fig. 5 is an enlarged vertical section through the holding dog and the casing for 40 the same; Fig. 6 is a detail elevation, showing the lock for the lower sash held in an inoperative position.

The window-frame 1 and the sashes 2 may 45 be of any preferred construction and form no part of my invention. Each sash is provided with a longitudinal recess 3 in its side edge which, when the sash is in position, will be concealed by the window-frame, the parting strip 4 and the bead 5, as shown 50 most clearly in Fig. 3. Within this recess 3, I secure a rack bar 6 which has one edge free and turned so as to lie parallel with and adjacent the inner edge of the parting strip or the front bead, as the case may be and 55 this free bent edge is constructed with ratchet teeth 7 having their longer sides in-

clined toward the sash and their shorter sides at a right angle to the side edge of the sash so as to present positive abutments to the action of the dog presently mentioned. 60 It will be understood that these racks or holding bars are so disposed that in the closing movement of the sash, the inclined edges 8 will ride readily over and past the holding dog but, upon an attempt being 65 made to open the sash, the shorter edge 7 of the ratchet teeth will be brought squarely against the free end of the holding dog so that the opening movement will be positively resisted unless the dog is released in a 70 manner which will be set forth.

The rack bars or holding racks will be made rights and lefts and, owing to the simplicity of these elements, both a right and a left rack may be formed at one time. 75 This is accomplished by forming the ratchet teeth along the side edges of a blank by the action of one die, then splitting the blank longitudinally into two parts, and then bending the serrated edges of the 80 blanks in opposite directions. The bars will, of course, be provided with suitable openings 9 through which fastening devices may be inserted to secure them in position, as indicated at 10.

The holding dog 11 consists of a sheet metal blank bent to provide the spaced lugs or perforated ears 12 at one end and provided along one edge with a handle member 13 which is so shaped as to project outwardly between the sash and the bead or the parting strip and then bent at right angles to provide the tip 14 to which pressure may be applied by the finger of the user, when desired. This arrangement is 95 shown most clearly in Fig. 3 of the drawings. The dog is pivotally hung within a casing 15 which is also struck up out of sheet metal and fits snugly within a recess or socket in the window frame, as shown at 100 16, perforated lugs or ears 17 being provided at the upper and lower ends of the casing to facilitate the securing of the device in position. A pivot pin 18 is inserted 105 through the upper end of the casing and the lugs 12 of the dog so as to suspend the same within the casing, and a spring 19 is disposed within the casing so as to normally hold the dog projected in position to engage the teeth of the holding rack, as shown 110 clearly in Fig. 5. This spring is illustrated as a resilient strip doubled upon itself and

having one branch bearing against the inner or back wall of the casing and its other branch in contact at its extremity with the main body of the dog near the lower end 5 of the same whereby the resiliency of the strip will be exerted to project the dog from the casing, as will be readily understood upon reference to Fig. 5.

From the foregoing description, taken in 10 connection with the accompanying drawings, it will be readily understood that when the window is closed it will be held in its closed position by the dogs engaging the square abutting edges of the ratchet teeth on the 15 holding racks and any effort to open the sash will simply force the said edge more firmly against the dog. If it be desired to open the window from the inside, for ventilation or other purposes, a slight pressure 20 upon the tip 14 will swing the dog against the force of the spring 19 and will thereby carry the holding end of the dog into the casing, as shown in dotted lines in Fig. 5, whereupon the sash may be readily moved. 25 As the dog is not accessible from the outside of the window, it will be obvious that the opening of the window, by unauthorized persons, will be prevented, while at the same time the window may be very easily 30 opened by the proper persons.

When the windows are being washed, it is very necessary that the sash may be moved freely and I, therefore, provide simple means whereby the lock may be held in an inoperative position. As shown in 35 the drawings, I pivotally mount upon the window frame a latch 20 which is constructed on one edge with a shoulder 21 adapted to engage over the tip 14 of the dog 40 and also constructed at its free end with a laterally bent portion 22 constituting a handle by which the latch may be manipulated. It will be readily understood that the latch will be pivoted at such a point that the 45 shoulder 21 or the tip of the latch may be swung into engagement with the finger or tip 14 of the holding dog so that when the latch is so engaged with the dog, the end of the latch will extend into the path of 50 movement of said tip and thereby hold the same withdrawn into its inoperative position.

My device is exceedingly simple in its construction and free of all complicated arrangement of its parts so that it may be produced and applied to a window at a 55 very low cost. When applied, it will be found highly efficient for the purposes for which it is designed.

60 It will be noted that the working faces or edges of the ratchet teeth are disposed at a right angle to the window sash and frame and the working edge which is engaged by

the locking dog will, consequently, extend across the arc defining the path of movement 65 of the free end of the dog. Moreover, the body of the dog extends from its pivotal end to its working end in a single plane free of all projections or offsets so that the locking strain is received squarely by the dog 70 and does not bend nor distort the same. Should an attempt be made to open the window from the outside, the opening movement will be positively resisted and the dog cannot be released until after a slight closing 75 movement has been given the sash. This closing movement obviously increases the distance which must be bridged by the intruder to reach the tip or push button 14 to release the dog and to that extent renders 80 nugatory his effort to raise the window, and consequently, frustrates his attempt to open the window. A window may, therefore, be safely left partly open for ventilating purposes. 85

Having thus described the invention, what is claimed as new is:

1. A device for the purpose set forth comprising a holding rack consisting of a sheet metal plate having one edge bent laterally 90 and provided with ratchet teeth having their holding edges disposed at a right angle to the longitudinal plane of the plate and their other edges inclined inwardly, a dog pivoted at one end and arranged to ride upon the inclined edges of said ratchet teeth during movement of the rack in one direction and to extend across and engage squarely against the working edges thereof upon movement of the rack in the opposite direction, and a handle member extending from one edge of said dog and having its extremity bent laterally to provide a pressure tip. 95

2. A sash holder comprising a casing to be secured within a window frame, a holding rack consisting of a metal plate to be secured to a window sash having one longitudinal edge bent laterally and formed with ratchet teeth, the working edges of said teeth being disposed at a right angle to the line of movement of the sash, a dog consisting of a sheet metal plate having one end provided with lugs and fitting within the end of the casing, and a handle member struck from one edge of the plate intermediate the ends thereof, a pivot inserted through the casing and said lugs, and a spring spanning said pivot and having one arm bearing against the casing and another arm bearing against the free end of the dog to project the same into engagement with the holding rack. 110

In testimony whereof I affix my signature.

JOHN CLAYTON BACKUS. [L.S.]
